UNITED STATES PATENT OFFICE.

ALVIN G. SHERMAN, GEORGE SMITH, AND GEORGE H. RAMIG, OF DETROIT, AND CYRIEL A. ROOSE, OF GROSSE POINTE FARMS, MICHIGAN, ASSIGNEES TO THE DETROIT VAPOR STOVE CO., OF DETROIT, MICHIGAN, A CORPORATION OF MICHIGAN.

HEAT-CONTROL DEVICE FOR OVENS.

Application filed May 19, 1926. Serial No. 110,085.

This invention relates to a heat control device for ovens. It has to do particularly with the provision of a novel, compact and extremely simple thermostat for controlling the supply of fuel to an oven and a novel manner of arranging the thermostat in combination with the oven.

It is the object of the present invention to provide a thermostatically operated valve structure for controlling the supply of fuel to the burners and novel means for directly adjusting the valve controlling parts with a minimum amount of mechanical motion, and with a minimum amount of wear on such various parts. A further object of the present invention has to do with the location of the thermostatically controlled valve and the various connected parts within the oven so as to present an oven and stove structure of pleasing appearance and with a minimum number of exposed parts. A still further object of the invention has to do with a novel manner of locating the heat control structure within the oven, whereby only the adjusting and indicating parts are on the outside of the oven, and a novel arrangement of said parts in combination with the oven whereby the various parts of the valve structure are readily accessible for cleaning from the outside of the stove without disassembly of any of the parts and without changing of the dial setting.

In the drawings:

Fig. 1 is a perspective view of a gas stove provided with our heat control device and showing the pleasing outward appearance of the stove.

Fig. 2 is a front elevation in vertical section taken on a plane just forward of the heat control device in Fig. 1 and showing the preferred manner of locating the heat control device within the oven and the connecting of the various pipes to the oven supply pipe.

Fig. 3 is a diagrammatical plan view of the structure shown in Fig. 1 and showing the heat control device and piping connections therefor in solid lines and the remainder of the stove in dotted lines.

Fig. 4 is a vertical longitudinal sectional view of our novel heat control device including the thermostatically controlled valve and the various connected parts, and also

showing the novel manner of adjusting the expansible member to initially set the valve.

Fig. 5 is a sectional view taken on line 5—5 of Fig. 4 and showing the inlet and outlet conduits leading to and from the valve structure.

Fig. 6 is a fragmentary front elevation of the structure shown in Fig. 4 and showing the indicating dial and handle and pointer member for adjusting the expansible member for setting the valve.

Fig. 7 is a fragmentary detail view taken on line 7—7 of Fig. 6.

Fig. 8 is a detail view taken on line 8—8 of Fig. 4 and showing the pivoted lever for moving the expansible member longitudinally of the non-expansible member and at the same time preventing rotation thereof.

Heretofore in the use of heat control devices for ovens, it has been the custom to mount the thermostatically controlled valve and various connecting parts on the outside of the oven. This outside mounting of the heat control structure, together with the various connecting gas pipes and parts, has heretofore presented a very cumbersome and unsightly stove unit, as well as taking up a large amount of space at the side of the oven.

The present invention overcomes such cumbersome locating of the heat control structure and connecting parts by locating the heat control structure as a unit on the inside of the oven in combination with the novel manner of securing such structure to the oven.

Referring to the drawings, which disclose one embodiment of the invention, the thermostatically controlled valve is shown as being mounted in an integral housing 1. This housing is best shown in Figs. 4 and 5 and preferably comprises an integral casting with a chamber 2 therein. This chamber 2 is provided with an annular valve seat 3 and such chamber is connected by means of a suitable inlet port 3' and outlet port 4.

The rear of the housing 1 is provided with a suitable aperture 5 adapted to receive and guide the stem of a valve 6. This valve is designed to seat against the annular seat 3 and is normally held in closed position by means of a suitable coil spring 7. This coil

spring 7 is located centrally about an inwardly projecting lug of a cap 8 which is secured in position by means of suitable set screws 9. This cap is designed not only to permit initial assembly of the valve parts but also to permit easy and accessible cleaning of the parts as will be presently described.

The valve stem 6 is designed to support one end of a suitable expandible tube 10 which may be made of copper, brass, or any other similar material having a high coefficient of expansion. This tube 10 is designed to receive a non-expandible member 11 of carbon, or similar material, one end of said member 11 abutting against one end of tube 10, and the other end abutting against, or positioned adjacent the end of the valve stem 6. It will be obvious that if the expandible member 10 is moved inwardly towards the valve that the valve will be moved from its seat against the pressure of the spring 7 and that if such expandible member 10 is heated to a sufficient degree, the expansion thereof permits movement of the member 11 to permit gradual closing of the valve.

One of the important features of our invention is the manner of operating and adjusting this expandible member 10. The housing 1 is provided with a suitable lug 12 for pivotally supporting a suitable lever 13. The upper end of this lever 13 is bifurcated and is designed to embrace the inner end of the tube 10 and to abut against a flange 14 of such tube. Suitable pins 15 are positioned on each side of tube 10 and slightly above the center thereof and are designed to prevent rotation of the tube about its longitudinal axis. Such prevention of rotation of the tube will obviously prevent any grinding or wearing action between the non-expandible carbon member 11 and the expandible tube. The lower end of the lever 13 is designed to contact with a suitable screw 16 which extends through and is threaded in the bottom part of the housing 1, and which screw also protrudes forwardly of such housing, whereby when the housing is assembled in the oven a part of the screw will project exteriorly of the oven. A suitable pointer 17 and handle 18 are mounted on the outer end of the movement of the lever 13, and rectilinear movement of the tube 10 and the valve 6. The handle 18 is preferably threaded in the pointer 17, and preferably extends through pointer 17 to engage and position the handle and pointer upon the screw rod 16. By this arrangement the handle and pointer may be readily removed, or they may be readily adjusted to initially adjust or permit change of the dial setting in accordance with the expandible and non-expandible members of the valve element.

15 The outside oven body may be designated

19, and is provided with a suitable rectangular aperture 20, and flanges 21 for receiving the cap 8 and to permit ready removal of said cap from the outside. The housing 1 is provided with suitable bosses 22 and 23, the bosses 23 being designed to be tapped to receive suitable cap screw 24, as shown in Fig. 6, for securing the housing unit 1 to the shell or lining 19 of the oven. A suitable shield, or cover 25 is designed to be secured to the exterior of the oven and so shaped as to cover the rectangular opening 20 and to also extend downwardly around the screw shaft 16. This shield is slotted as at 26 and the lower end of such slot is designed to receive a suitable set screw 27 for securing the shield in place, as shown in Fig. 6. The set screw 27 is adapted to screw into the boss 22 as best illustrated in Fig. 7. This set screw serves two purposes, in that, it serves as a means for stopping the pointer in its two extreme positions, and also serves as a means for permitting rotation of the shield 25 to make it possible to readily clean the valve structure from the outside of the oven. It will be obvious that by removing the set screw 27 that the shield may be rotated about the screw 16 and then lowered by means of the slot 26 so as to make the rectangular opening 20 readily accessible. It will also be obvious that the handle 18 and pointer 17 being once set on the screw 16, that the valve structure of the housing may be cleaned without disturbing the setting of the thermostat.

100 By securing the thermostat to the inside of the oven by means of the screws 24 and set screw 27 it is possible to conceal the piping leading to and from the thermostat housing. As best shown in Figs. 2 and 3 105 the inlet and outlet pipes 28 and 29 extend directly downwardly from the housing 1 within the oven. The inlet pipe 28 is suitably connected to the oven valve by means of a suitable conduit 30, and this inlet pipe 110 may be provided at its base with a suitable pilot light burner 31, as shown in Fig. 2. The outlet pipe 29 from the thermostat which leads to the oven burners 32 preferably extends to the exterior of the oven 115 casing and beneath the hot plate of the range so that it is obscured from general view. It will be understood that such connecting pipe between the pipe 29 and the mixer for the burners may be positioned on the inside of the oven if desired, but the arrangement shown in Fig. 3 is the preferred form.

120 In operation, the various pipe connections having been installed as illustrated, it will be obvious that the set screw 16 may be turned to contact with the pivoted lever 13. The pointer 17 may then be inserted upon the end of the screw shaft 16 and the handle 18 screwed into place whereby the pointer 130

17 may be secured to the screw shaft at the desired position in accordance with the length of the expandable or non-expandable members 10 and 11 and the position of the 5 valve member 6. It will be understood that a suitable indicating dial may be positioned or formed on the exterior of the shield 25, as illustrated in Fig. 6 and the handle pointer having been set to the desired position, the handle may then be turned so that the pointer 17 is positioned at the temperature to which it is desired that the oven be heated up to. This turning of the handle 18 will open the valve 6 and admit gas to 10 the oven burners, and as the oven gradually approaches the temperature corresponding to the setting of the dial the tube 10 will expand and lengthen to such a degree that the valve 6 will gradually tend to close and 15 thus restrict, or stop the flow of gas to the burner in order to maintain the temperature to which the pointer is set.

It will thus be seen that we have provided a novel heat control unit which may be 25 quickly and easily placed on the inside of the oven and completely enclosed from view with the exception of the handle and dial for controlling the operation of the heat control unit. It will further be obvious that 30 we have provided a novel arrangement of thermostatically controlled valve and means for operating and adjusting the same whereby the setting may be quickly and easily obtained or corrected, and which heat control unit is so arranged in combination with 35 the oven that the parts of the thermostatically operated valve may be quickly and easily obtained or corrected, and which heat control unit is so arranged in combination 40 with the oven that the parts of the thermostatically operated valve may be quickly and easily cleaned from the exterior of the oven without the dismantling of any of the parts.

What we claim is:

45 1. A heat control device for ovens or similar structures, comprising in combination a heat control unit secured to the interior of the oven, the oven having an opening adjacent said heat control unit and a shield on the exterior of the oven readily removable to permit access to said heat control unit.

50 2. A heat control device for ovens or similar structures, comprising in combination a heat control unit adapted to be positioned 55 on the interior of the oven, means insertable from the exterior of the oven for securing the unit to the oven wall and readily removable means for covering said securing means and serving as an indicator for said heat control unit.

60 3. A heat controlling device for ovens and the like, comprising a housing positioned on the interior of the oven wall, temperature controlling means within said housing, an ex-

pansible and a non-expansible member, and 65 means pivotally mounted on said housing for moving one of said members only to actuate said temperature controlling means.

4. A heat control device for ovens or similar structures comprising a housing positioned within the oven, heat responsive means carried by the housing, a shaft carried by and projecting from the housing, a member pivotally carried by the housing and connecting the shaft and heat responsive 70 means for positioning said heat responsive means and an operating and indicating means both adjustably secured to said shaft whereby the setting of the heat control device may be readily corrected. 80

5. A heat control device for ovens or the like, comprising a heat control unit mounted on the interior of the oven, a shaft for controlling the operation of said heat controlling device projecting from said oven, indicating means secured to said shaft, and an operating handle for adjustably and removably securing said indicating means to said shaft and operating the shaft through the indicating means. 85

6. A heat controlling device for controlling the temperature within an enclosure, comprising a housing secured to an interior wall of said enclosure, a chamber in said housing for receiving temperature control- 95 means, a cap for chamber and means operable from the exterior of the enclosure for permitting ready removal of said cap.

7. A heat controlling device for ovens or the like, comprising in combination a housing secured to the interior of the oven, means on the exterior of the oven for regulating said device and means movable to permit cleaning or inspection of said device from the outside of the oven, without changing 105 the setting of said regulating means.

8. A heat control device for ovens or the like, comprising a housing mounted on the oven wall within the oven, temperature control means in the housing, heat responsive 110 elements supported by this housing and projecting therefrom inwardly of the oven and away from the said oven wall, means carried by this housing eccentric of the temperature control means and projecting through 115 the oven wall for adjusting the heat responsive elements.

9. A heat control device for ovens or the like, comprising a housing mounted on the oven wall within the oven, temperature control means in the housing, heat responsive elements supported by this housing substantially concentrically with the temperature control means and projecting inwardly 120 of the oven away from the said oven wall, and means carried by the housing eccentric of both the temperature control means and heat responsive elements, said last named 125

means projecting through the oven wall and operable from the outside of the oven to adjust the heat responsive elements.

10. A heat control device for ovens or the like, comprising a housing mounted on the oven wall within the oven, temperature control means in the housing, heat responsive elements supported by this housing substantially concentrically with the temperature control means and projecting inwardly of the oven away from the said oven wall, a shaft carried by this housing eccentrically of both the temperature control means and the heat responsive elements, said shaft projecting through the oven wall, means operatively connecting the inner end of the shaft with at least one of the heat responsive elements, and means on the outside end of the shaft operable to adjust the heat responsive elements.

11. A heat control device for ovens and the like, comprising a housing mounted as a unit inside the oven wall, a temperature controlling valve in the housing, a thermostatic element mounted on the housing in alignment with the valve, gas pipes positioned within said oven wall and extending to and from said housing, and means carried by said housing eccentric of the axis of the

valve member and projecting through the oven wall to permit adjustment of the thermostatic element.

12. A heat control device for ovens and the like, comprising in combination a housing including a temperature controlling unit and a thermostatic element mounted as a unit in the interior of the oven, gas pipes positioned within the oven and extending to and from said housing, a shaft extending through said housing one end projecting outwardly through the oven wall and the other end extending inwardly past the housing, a member secured to the housing and directly connecting the inner end of said shaft with said thermostatic element, the oven lining being provided with an opening for permitting access to the housing, a shield for covering said opening and serving as an indicator, and a combined handle and pointer secured to the outer end of said shaft for cooperating with said shield.

In testimony whereof we have affixed our signatures.
